[57] ABSTRACT

A plurality of graphic images, which may be electro-photographically produced and which are removably disposed in alignment longitudinally of a web arranged for movement in a lineal path between supply and take-up stations, are contact transferable in rows to a card which is arranged for movement intermittently transversely of the path of movement of said web.

APPARATUS AND PROCESS FOR GRAPHIC IMAGE TRANSFER

This is a division of application Ser. No. 160,890, filed on July 8, 1971, now abandoned, which in turn was a division of patent application Ser. No. 695,228, filed Jan. 2, 1968, now U.S. Pat. No. 3,612,685.

The present invention relates to graphic records. Particularly the invention relates to formation of a visual record by image transfer from a first to a second visual image carrier. Specifically the invention relates to apparatus and a process for transferring successive aligned graphic images which may have been electrophotographically formed in a line longitudinally of a web or first carrier onto a second carrier as a plurality of successive rows of images.

A prior but recently developed process in electrophotography enables production of graphic images whose densities and resolutions approach those which can be achieved through the medium of silver halide films. In accordance with such prior process, particulate of a photoconductive insulative layer of an electrophotographic lamination is treated to form a plurality of aligned visible images longitudinally of a metallic layer supported on a flexible film web as it is moved from a supply source to a take-up station. However, the images are not permanently secured to the web as the particulate is only electrostatically attracted to the metallic layer. In consequence thereof, the web can be considered only a temporary or impermanent image carrier. That is to say, after image formation, further steps are required to make a permanent graphic record.

While various expedients might be conceived for permanently affixing the electrostatically held images to their web, the product thus produced would be satisfactory only for some purposes. It would not, however, be readily adapted for easy addition of relevant intelligence at or near any given image. This characteristic is more readily available when visual images are carried in successive rows on, for example, cards.

It is an object of the present invention to provide an improved process and apparatus for forming a graphic record.

It is another object of the invention to provide an improved method and apparatus for contact transfer of graphic images in formation of a permanent record.

It is a further object of the invention to provide an improved graphic record in which the images are produced by an electrophotographic process.

It is an additional object of the invention to provide a permanent visual record from particulate comprising a photoconductive insulative layer of an electrophotographic lamination.

It is moreover an object of the invention to provide a record card having successive rows of images.

It is yet a further object of the invention to transfer images from an aligned position on a web to successive rows on a record card and the like.

The features of the invention by which the foregoing objects are effected comprise an image transfer station which is provided in apparatus for producing a visual record having a plurality of successive rows of graphic images. First supporting means are arranged for moving a first carrier with transferable graphic images in a path relative the image transfer station, and second supporting means enable moving a second carrier in image-receiving association with and transversely of

the path of the first carrier at said image transfer station. Image-applying means are provided for transferring the graphic images at the transfer station and from said first carrier into rows on said second carrier. The images may, but need not, be formed in an electrophotographic process of the particulate from which a photoconductive insulative layer of an electrophotographic lamination is fabricated. If they are so formed, the first carrier comprises a conductive layer included in said electrophotographic lamination, and the graphic images are physically transferred from a single row on the first carrier to a plurality of successive rows on said second carrier for producing a permanent visual record.

The foregoing and other objects, features, and advantages of the present invention will become more apparent upon consideration of the following description and appended claims when considered in conjunction with the accompanying drawings wherein the same reference character or numeral refers to like or corresponding parts throughout the several views.

On the drawings:

FIG. 1 is a front elevational view of apparatus embodying one form of the invention.

FIG. 2 is a view according to the section line 2—2 of FIG. 1.

FIG. 3 is a fragmentary rear elevational view according to the line 3—3 of FIG. 2.

FIG. 4 is a view according to the broken section line 4—4 of FIG. 1.

FIG. 5 is a view according to the section line 5—5 of FIG. 1.

FIG. 6 is a view according to the section line 6—6 of FIG. 5.

FIG. 7 is a fragmentary view in perspective of a plurality of switch-actuating cams for operating said apparatus.

FIG. 8 is an electrical wiring scheme for said apparatus.

FIG. 9 is a cross sectional view of an electrophotographic lamination prior to development and drawn to a scale enlarged from the scale of FIG. 1.

FIG. 10 is a view similar to FIG. 9, however showing the electrophotographic lamination following development.

Having reference now more particularly to FIG. 1 and FIG. 2 of the drawings, a chassis or framework generally designated 11 comprises a base 13 from which a front vertical hanger plate 15 projects for rotationally supporting a film takeup reel 17 which defines a takeup station. With lamination supply means defining a supply station 16, reel 17 provides first supporting means for an impermanent, temporary or first carrier 19 which is movable in a path longitudinally of the web forming said carrier and relative to an image transfer station generally designated 21. As illustrated in FIG. 10, first carrier 19 provides support for material defining a graphic or visual image 25 which is adapted for transfer in a manner which will become apparent from ensuing description.

In the embodiment of the invention illustrated, image 25 consists of the residue of particulate or particles after development of a photoconductive insulative layer 27 of an electrophotographic lamination or sandwich 29 (shown undeveloped in FIG. 9). However, as it will be appreciated, all aspects of the invention are not limited to image formation in the particular manner described. That is to say, the invention comprehends

graphic image formation by any suitable means, including electrical, mechanical, or chemical techniques.

Nevertheless, as illustrated, electrophotographic lamination 29, prior to development, is introduced from supply station 16 and comprises a soluble thermoplastic removable insulator disposed in a layer 31 between photoconductive insulative layer 27 and a metallic layer 33 of, for example, aluminum. The latter, together with a flexible web or film 35 of, for example, mylar, to one of the opposite faces of which layer 33 is bonded, forms first carrier 19 after development. Preferably the photoconductive insulative layer 27 is composed of selenium particles having a dimension of about 0.2 microns. The thermoplastic layer 31 is approximately 2.0 microns thick, and the aluminum layer 33 is about 73 percent light transmissive and sufficiently thin so that first carrier 19 is flexible. To that end, and to enable storage of lamination 29, prior to development, at supply station 16, and to enable storage of image carrier 19 on takeup spool 17, after development, web or film 35 is between 0.005-0.007 inch thick.

If image 25 is formed in accordance with the herein described embodiment, layer 27 is charged statically prior to exposure by employing a corona technique. For that purpose, layer 33 must be grounded. Thereafter, electrophotographic lamination 29 is exposed in a conventional manner, such as by projection or by contact, to form a latent image in layer 27. Subsequently, layer 31 is removed by dipping the laminations member 29 into a thermoplastic solvent for washing away said last named layer as well as portions of particulate which are non-image-forming. Remaining after such washing and after evaporation of the solvent from the product removed from the wash, is first carrier 19 on layer 33 of which selenium particulate corresponding to the latent image theretofore produced becomes attached as a physical image, as illustrated in FIG. 10. However, the bonding is weak, and transfer of image 25, in a manner which will be described presently, is therefore facilitated. Moreover, as the aforesaid image formation process permits creation of a plurality of aligned temporarily held images longitudinally of first carrier 19, these images can be applied, in accordance with the present invention, in successive rows on a second or receiving card or carrier 37 at image transfer station 21 as first carrier 19 is moved toward takeup reel 17 for presenting the thereon supported images in sequence at said transfer station.

Second carrier 37, which may become a permanent visual record, is releasably secured on a rotatable drum 39 by suitable clamp means 41 (FIG. 1). Drum 39 comprises supporting means for moving carrier 37 during successive periods into image transfer association with carrier 19, and to that end said drum is supported at image transfer station 21 and is arranged concentrically of and for co-rotation with a shaft 43, for rotating second carrier 37 adjacent the image-carrying face of web 35 into image-receiving aspect at said station about an axis extending transversely of the path of first carrier 19.

Drum 39 is also arranged for intermittent linear or axial movement; that is to say, movement transversely of the path of movement of first carrier 19. Transverse or axial drum movement is accomplished through the medium of a supporting assembly means comprised of a pair of horizontally spaced vertical bearing blocks 45

and 47 in which shaft 43 is journalled and which, together with a vertical force transmission plate 49, are rigidly secured to a carriage 51. The latter is included in means for relatively moving carriers 19 and 37, and is slideable along chassis base 13 on a thereto fixed horizontal track 53 which extends transversely of vertical front hanger plate 15 and a thereto parallel fixed rear hanger plate 55 (FIG. 2).

A motive means or reversible motor 59 is arranged for reversibly driving drum 39 through the expedient of a sprocket band 57 which is arranged in operable association with a pair of sprockets 61 and 63. The former is secured to the shaft of motor 59 and the latter is secured on shaft 43. The face plate of motor 59 is rigidly secured to an upward extension 65 of bearing block 45. Thereby, motor 59 is adapted for movement with drum 39 and its supporting assembly.

In the illustrated embodiment, images are pressure-transferred or removed from first carrier 19 and applied onto second carrier 37. To effect the transfer, the image receiving areas of carrier 37 are coated with a conventional material 67, such as a soluble plastic, which is normally hard but capable of becoming tacky to develop an affinity for the image material sufficient to overcome the force with which the images are held on first carrier 19. To the end that first carrier 19 may be brought into transfer association with successive parts of second carrier 37, an air operated cylinder 69 is supported from front hanger plate 15 by a bracket 71 which is proportioned to accommodate vertical reciprocation of reciprocal means, fluid operated member or piston 73 of said air cylinder. An assembly including a roller 75, which is included in said reciprocal means, is carried on the lower end of said piston, and is arranged so that roller spindle 77 extends transversely of the path of movement of first carrier 19. The arrangement is such that the circumference of roller 75 is disposed adjacent the non-image carrying face of web 35 to intermittently drive said image-containing face against second carrier 37 as piston 73 reciprocates between a first position in which said first and second carriers 19 and 37 are disposed in image impinging association for image transfer and a second position in which image transfer is prevented.

Constant tension on first carrier 19 which causes its engagement with roller 75 results from torque of tensioning means comprising a takeup motor 79 which is mounted behind front hanger plate 15 for driving takeup reel 17 through a gear train 81 (FIG. 4). In the present embodiment, however, the takeup torque is insufficient to draw first carrier 19 longitudinally of its path. Such movement is effected by the traction generated by the torque of drum 39 as it rotates and the force with which roller 75 impinges first carrier 19 against second carrier 37.

To the latter end during which image transfer occurs, air is conducted through a conduit 83 (FIG. 3) from its supply source (not shown) through a valved body 85 for controlled flow through a conduit 87 to cylinder 69 which comprises means for reciprocating roller 75 into and out of frictional association with carrier 19. A solenoid 89 (FIG. 8) is arranged in body 85 for controlling its valve and accordingly the air pressure in cylinder 69. The air thus delivered forces piston 73 downwardly against its normal spring biasing to impel carriers 19 and 37 relative one another to effect image transfer by contact of image 25 with thereon aligned

material 67. The period for which the piston remains at the limit of its downstroke can be adjusted in accordance with requirements of the evident variable factors so that a length of only a desired segment of first carrier 19 will be impinged against carrier 37 at any one downstroke, to permit precision transfer of thereon supported images. The normal tensioning on first carrier 19 caused by takeup reel 17 will insure that carrier 19 will follow the roller 75 when piston 73 retracts.

Operating in synchronization with solenoid 89 is an indexing mechanism generally designated 91 (FIG. 2) for moving a member such as drum 39 axially intermittently to successive positions in which successive axially spaced areas of material 67 are aligned with roller 75 for rotation through station 21. That is to say, after image 25 from a section of first carrier 19 of predetermined length has been transferred to second carrier 37, drum 39 will be moved axially for delivering successive portions of second carrier 37 into alignment with a following segment of first carrier 19 for transfer of a succeeding image then disposed at station 21, and so on, until a successive number of rows of images has been applied to second carrier 37.

Control of the tackiness of material 67 is effected by a solvent 93 which is stored at a source in supply means being a reservoir 95 (FIGS. 4 and 5). As illustrated in FIG. 2, a trough 97 is constrained for movement with carriage 51 by reason of a mounting assembly 99 which through fasteners 101 secures said trough to bearing block 47. Thereby, a fixed relationship is maintained between drum 39 and said trough into which said drum partially extends for rotation in a manner such that material 67 to which image 25 is being transferred at any given time is disposed outside of said trough.

Liquid receiving means comprising a conduit 103 transfers solvent 93 between reservoir 95 and through 97. At its downstream end, conduit 103 is connected to a vaporizing chamber 105 which is mounted below and for movement with the trough. A vent 107 (FIG. 2) enables escape of solvent gases from chamber 105 into the trough where material 67 is suitably softened by vaporized solvent as drum 39 rotates, to effect image transfer.

Heating means comprising an electric heater element 109 is arranged with respect to chamber 105 for vaporizing therein contained solvent. To appropriately control the heater element, an adjustable thermal switch 113 (FIG. 8) is connected in a heater circuit 111. An indicator light 115, which is shown connected in parallel with heater circuit 111 by conductors 117, is mounted in a chassis-supported control panel 119 (FIG. 1) for obvious intelligence purposes because it may be deemed desirable from time to time in order to control the tackiness of material 67 to disconnect heater element 109 from the power source (Not shown).

Control of delivery of solvent 93 from reservoir 95 is through the medium of solvent metering means generally designated 120 (FIG. 4) which is in fluid communication with the upstream end portion of conduit 103. Said fluid metering means comprises a valve body or housing 121 which is arranged for intermittent fluid transmission by gravity flow between solvent reservoir 95 and conduit 103. It is secured by suitable fasteners 123 to a boss 125 which is fast to chassis 11. Valve housing 121 has a tapered seat in which a tapered valve 127 rotationally engages by means of a compression

spring 129 which is arranged about valve stem 131 between an end of housing 121 and a bearing assembly 133 which is secured on said valve stem in spaced relationship from an end of said housing. Valve 127 is co-rotational with stem 131 for successively moving each of a plurality of outwardly opening wells 135 and 137 which are formed in said valve first into solvent-receiving condition and thereafter into solvent-delivering position. To that end, valve housing 121 has a plurality of bores 139 and 141 arranged for registration with wells 135 and 137 as they rotate past said bores. The downstream end of a delivery duct 143 which projects from reservoir 95 is connected in a fluid-tight seal to housing 121 with its lumen in registration with bore 139. The upstream end of conduit 103 is connected to housing 121 with its lumen in registration with bore 141. In the present illustration, wells 135 and 137 are spaced in diametric opposition so that while one well fills from reservoir 95 the other empties into conduit 103.

Means for effecting rotation of valve stem 131, and accordingly valve 127, comprises continuously driven motor 145 on the output shaft of which a cam 147 is co-rotationally mounted intermittently to move a normally open micro switch 149 to close a circuit 151 (FIG. 8). A motor 153 which rotates at a different rate from motor 145 is arranged to be intermittently energized for rotation by circuit 151. Motor 153 has an output shaft 155 which is connected by coupling means 157 to a projection of valve stem 131 for driving valve 127. It is appreciated that the parts are synchronized for delivering sufficient fluid to chamber 105 through the medium of cam 147, the dwell and throw of which are proportioned so that motor 153 will become energized and de-energized for sufficient periods to insure maintenance of the quantity of fluid delivered to chamber 105 within a pre-selected range.

In the illustrated embodiment, indexing mechanism 91 comprises driven means, here shown as a double acting air cylinder 159 (FIGS. 2 and 4) which is mounted from rear chassis plate 55 with its reciprocative piston or rod 161 secured by opposed fasteners 163 to plate 49. Rod 161 is a driven member which is arranged for moving drum 39 axially thereof and is included in means for relatively moving said carriers 19 and 37. Indexing movement, that is to say movement of carriage 51, from the position of FIG. 2 to the right thereof, to motivate drum 39 at successive intervals transversely of the path of first carrier 19, is controlled by air pressure in cylinder 159 transmitted to one end thereof by air tube 167. The latter is in fluid communication with an air supply source (not shown) through a valved structure 165 which is connected to air supply tube 169. The valve of structure 165 is controlled by a solenoid 171 (FIG. 8) which is arranged for intermittent motivation, as will become presently apparent, to produce drum-advancing pressure. For fine control of indexing movement to insure that only predetermined successive portions of the second carrier 37 are presented at image transfer station 21, control means in the form of a rack or ratchet 173 is mounted for sliding movement in the rear chassis plate 55 parallel to and together with rod 161. Rigid securance of the forward end portion of said rack and plate 49 by suitable fasteners 175 causes such simultaneous movement. The rear portion of rack 173 has a plurality of notches 177 (only two of which have been numbered in FIG. 2) which are

spaced from each other for moving drum 39 intermittently successive distances according to the pitch of said notches. Thereby, only desired portions of second carrier 37 will be presented at image transfer station 21. A detent 179 is connected to rear chassis plate 55 by a bracket 181 from which said detent is rockably hung for removable selective engagement in said notches for restraining axial movement. The condition of the detent is responsive to solenoid 183 from the magnetically retractable arm 185 of which the detent is pivotally connected by a link 187 and by means of which the detent may be moved from holding position when solenoid 183 is energized.

The apparatus is controlled from a power circuit 189 which is shown with a plug 191 for connection to a power source. A lamp 193 is connected in parallel with the power circuit, and is supported in control panel 119 (FIG. 1). Also mounted in the control panel is the manual component of a switch 195 for connecting motor circuits 197 and 199 with power circuit 189, thereby to enable operation of motors 145 and 153 of solvent-metering means 120. The control-panel-hung manual component of a switch 201 is arranged to connect a transformer 203 into power circuit 189, whereby heater element 109 as well as lamp 115 become energized. A manual control member of a switch 205 is also mounted in control panel 119. The last switch is arranged to connect the circuit 207 of motor 59 to power circuit 189. For reversibly driving said motor, circuit 207 has two sets of terminals as shown at 209 and 211 for selectively causing current flow in alternate circuits. The circuit 213 of takeup motor 79 is arranged for connection to power circuit 189 through the medium of a manually operated switch 215, the control component of which too is mounted in panel 119. The circuits controlled by switches 195, 201, 205, and 215 are independently operable each from the other and also from a circuit assembly 217 with a manual component which is also mounted in panel 119.

For the purpose of this description, the apparatus is considered as being operative in cycles, each having two phases and during which carriage 51 moves from and returns to the position of FIG. 2. During the image transfer part of the cycle, carriage 51 is motivated in successive steps to an extreme position to the right from its position of FIG. 2. During the other part of the cycle, carriage 51 is returned.

Solenoid 89 for controlling the flow of air to cylinder 69, solenoid 183 for controlling the condition of detent 179, and solenoid 171 which controls air flow through valved structure 165 for projection of rod 161, and all of which operate during the image transfer part of the cycle of the apparatus, are arranged in circuit assembly 217 which is conditioned for connection to power circuit 189 when a double throw switch 219 closes against terminals 221 and 223. For the return part of the cycle, switch 219 is closed against a pair of terminals 225 and 227 to open circuit assembly 217 and condition a circuit 229 for connection to power circuit 189.

A solenoid 231 which controls the valve in a valved body 233 (FIG. 3) is arranged to be energized by said circuit 229 for controlling flow through said last valved body. A duct 235 is arranged to establish air communication through valved body 233 between the forward end of cylinder 159 and an air duct 237 which connects with an air supply source (not shown). The arrangement is such that air supplied to cylinder 159 through

air duct 237 will cause rod 161 to retract from an extended position, thereby to return carriage 51 and, accordingly, drum 39, to about the position of FIG. 2. To prevent carriage 51 from being overdriven to the left on its return to the position of FIG. 2, a micro switch 239 (FIGS. 2 and 8) is mounted in a fixed position relative the chassis 11. It is disposed in the path of and adapted to be thrown by a lug or boss 241 which is arranged for movement with carriage 51, thereby to open circuit 229.

Operating the apparatus for image transfer requires not only closure of switch 219 against terminals 221 and 223, but simultaneous forward drive of motor 59, because a plurality of cams 243, 245 and 247 which are co-rotational with shaft 43 control phenomena in circuit assembly 217 through operation of micro switch 249, 251 and 253 (FIG. 7). The latter members are mounted in alignment with said cams, respectively, and for movement with carriage 51 by reason of securance by tie rods 256 to a hanger plate 255 which is rigidly secured to said carriage. The actuating arm of each of micro switches 249, 251 and 253 terminates in a cam follower which is normally biased into peripheral engagement with its respective cam.

Micro switch 249 is arranged for connection to terminal 223 through a conductor 258 in which solenoid 171 is connected in series. Connection to terminal 223 is achieved during a protracted period of each cycle of cam 243 during which micro switch 249 is closed against its terminal 257. The circuit thus established is completed to terminal 221 through a circuit wire 273 to which terminal 257 is connected by a circuit wire 259. The parts are arranged and proportioned so that when the follower of micro switch 249 engages in the dwell of cam 243, the circuit through conductor 258 will be broken, solenoid 171 will be de-energized, and air supply to cylinder 159 through air tube 167 will be interrupted. On the other hand, when the follower of micro switch 249 is engaged against the throw of cam 243, air pressure tending to project rod 161 to the right with respect to FIG. 2 will be introduced into cylinder 159 through air tube 167.

When the follower of micro switch 249 enters the dwell of cam 243, switch 249 will close against a terminal 261. Thereby, during each cam cycle, a circuit from terminal 223 to terminal 221 will be completed through the solenoid 263 of an alternate action relay for shifting its switch 265 from terminal 267 or 269, whichever is then engaged by switch 265, to the then disengaged of said terminals. As will hereinafter more fully appear, switch 265 comprises means by which drum 39 advances only when roller 75 is out of tractive engagement with carrier 19. The circuits of micro switches 251 and 253, accordingly, alternately will be conditioned for connection to terminal 223 through a circuit wire 217. Completion of the circuit to terminal 221 through micro switch 251 is through a conductor 272 arranged between said last switch and circuit wire 273. Completion of the circuit to terminal 221 through micro switch 253 is also through circuit wire 273 which is connected to said last switch.

Solenoid 183 is serially connected in a conductor 275, the opposite ends of which are connected to a terminal 277 and the aforesaid terminal 267. Micro switch 251, which is normally in closed condition against terminal 277, in the present embodiment of the invention, is arranged for motivation to open condition

by the throw surface of cam 245, thereby to deenergize solenoid 183 and force detent 179, under its normal biasing, toward rack 173. Cams 243 and 245 are arranged and proportioned first for energizing solenoid 183 and withdrawing detent 179 from a notch 177 while extending force is applied on the rod 161, and then for releasing said detent prior to release of the extending force on rod 161 so that upon such release the detent will drop back on the rack to be cammed by an engaged of horizontal camming surfaces 285 (FIG. 2) into the next succeeding slot and thereby stop advance of drum 39 at a predetermined position.

Overdriving of drum 39 to the right from its position of FIG. 2 is prevented when boss 241, heretofore described as fixed for movement with carriage 51, throws a micro switch 279 (FIGS. 2 and 8) to an open position, as shown in dotted lines in FIG. 8, from its normally closed position, thereby to break the circuit path to terminal 221 and, accordingly, the circuit for projecting rod 161.

As a result of the foregoing arrangement, solenoid 89 can be energized only during alternate cycles of cam 245. Consequently, roller 75 only then can be driven into image transfer and moving condition for first carrier 19. Moreover, roller 75 will be in operative condition only for a fraction of the period during which relay switch 265, which is included in means for alternating movement of carriers 19 and 37, is closed against terminal 269. Such control is exercised through cam 247 which is proportioned for closing switch 253 against a terminal 283 for a continuous fractional portion of the cam cycle for completion of a circuit between terminals 221 and 223 through circuit wire 273. This causes energization of solenoid 89 which is serially connected in conducting means 281 whose opposite ends comprise terminals 283 and 269.

By reason of the foregoing, first carrier 19 is prevented from disposition in image transfer association with drum 39 while the drum is moving axially. Furthermore, even though drum-advancing force is applied during each cycle of cam 243, such advancing force is thwarted in alternate cam cycles by detent 179 during which times roller 75 is driven into image transfer position at station 21.

As many substitutions or changes could be made in the above described apparatus and process, and as

many apparently widely different embodiments of the invention within the scope of the claims could be constructed without departing from the scope and spirit thereof, it is intended that all matter contained in the accompanying specification shall be interpreted as being illustrative and not in a limiting sense.

I claim:

1. An indexing mechanism for intermittently delivering successive portions of a member to a relatively fixed station and comprising: A rack mounted for movement longitudinally thereof in a first direction for moving said member intermittently successive distances according to the pitch of rack notches; driven means for impelling said rack for movement; a detent arranged for selective engagement in said rack notches for holding said member from moving, and means for moving said detent from member-holding condition to permit said member to move, and means connected to said rack and rotationally supporting said member for movement longitudinally of said rack.
2. An indexing mechanism according to claim 1 characterized by motive means for rotating successively delivered portions of said member at said station and mounted for movement with said rack.
3. An indexing mechanism according to claim 1 in which said rack has a plurality of surfaces leading into successive rack notches, and having means for releasing said detent after movement from holding condition for camming engagement with one of said surfaces while said rack is moving.
4. An indexing mechanism according to claim 3 in which the means for releasing said detent comprises an electrical circuit including a solenoid for moving said detent alternately with its release and electrical means responsive to the condition of said member for energizing and de-energizing said solenoid.
5. An indexing mechanism according to claim 1 characterized by hydraulic means for moving said rack in the first direction and in an opposite direction for commencement of movement in the first direction; valved means arranged for controlling fluid flow to said hydraulic means for selectively moving said rack in said opposite direction, and electrical means for controlling the condition of the valved means following completion of movement of said rack in said first direction.
